(57) **CLAIM**

The ornamental design for a rotatable control panel, as shown and described.

DESCRIPTION

FIG. 1 is a front perspective view of a rotatable control panel, showing our new design in an unclaimed usage environment;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

Broken lines are shown for illustrative purposes only and form no part of the claimed design.
